UNITED STATES PATENT OFFICE

2,562,644

DEVICE, PARTICULARLY FOR THE RAPID
FORGING OF WORKPIECES OF CEN-
TRALLY SYMMETRICAL CROSS SECTION

August Sixer, Thalwil, Zurich, Switzerland

Application August 6, 1948, Serial No. 42,758
In Switzerland August 15, 1947

2 Claims. (Cl. 78—21)

1

The present invention relates to forging apparatus and particularly to a special construction and arrangement of hammer-like elements and their supporting bearings, which elements, distributed in multiple arrangement at definite angular distances over a circle or a circular area or lying over each other in stepped sets, uniformly and positively take part in the non-cutting shaping or forging of an axially symmetrical workpiece.

In this respect several suggestions have already been made with reference to the hammerhead supporting bearings, which are particularly delicate and extremely highly stressed. With these methods of working, it is an essential condition that the hammerhead must be guided and lubricated with special care if the work is to be performed without any service difficulties. Above all, hammer-like workpiece-carriers supported in the manner of a cross-head are unsuitable for the slight travel and the high specific surface pressures. When it works in the manner of a crosshead, the workpiece-carrier has solely a reciprocating movement, and the front end of the connecting-rod makes a rotary swinging movement in the cross-head. Since in these constructions the known ballhead in the pan executes only slight movements which are unsuitable for forming a lubricating film, the head will in time seize in the pan, so that proper functioning of the device will become questionable.

It has therefore been proposed to avoid using the ballhead and pan by constructing the connecting-rod itself as workpiece-carrier and supporting this connecting-rod head in a sliding block, this latter having such a shape and construction that the connecting-rod head has free play to move. This device has proved thoroughly good in practice and is now adopted for use, no matter whether one is dealing with the forming of grooves in axially symmetrical workpieces, or whether axially symmetrical workpieces are being given an external shape by rapid forging by means of this device, whereby either a profile—circular or edges—is imparted to the workpiece through its diameter being altered, or grooves of various shape are pressed into it with the workpiece remaining stationary.

In practice, the above described arrangement has a drawback which indeed is not of such great importance because of the smallness of its spatial dimensions and of the great number of hammer blows, but which must be avoided in certain workpieces, namely the fact that the hammerhead executes a swinging movement round the

middle of the workpiece which the workpiece does not completely follow. Practically, this results in a crumpling movement of the tool in or on the workpiece and therefore in a slight widening of the groove edges when such grooves are being made, or in a rubbing on the periphery of the workpiece in the case of surface treatment of such workpiece to achieve non-cutting shaping of the diameter. The aim and intention of the present invention is to remove this last drawback and at the same time to avoid using a sliding block.

The essential characteristic of this invention consists in that the connecting rods (which carry the tools, or the heads of which are themselves formed to provide the tools) are arranged to slide in recesses of a carrier; said carrier being arranged to follow the swinging movements of the connecting rods and, while so doing, to oscillate about its own central axis.

Here it should at once be noted that the invention is applicable to an arrangement with a single connecting-rod, but this can of course be increased in accordance with the aim required, so that several connecting-rods are distributed round the periphery, spaced at regular or irregular angular distances from each other, work in a carrier. No special shape-determining connection between the members of the connecting-rod drive and the carrier for the connecting-rod heads is required, since no canting can occur when the former are exactly adjusted with respect to the latter.

In accordance with a further feature of the invention, the connecting-rod support is constructed as a swinging disk in which the connecting-rods themselves work in accordance with the purpose desired. This support is loosely pivotably supported and constructed in such a way that the connecting-rods can easily be inserted.

A still further feature of the invention consists also in the workpiece being able to partake in the swinging movement of the holding member for the moving of the connecting-rods. Finally the device is also characterised by the workpiece being able to execute, in addition to the swinging movement, also an additional axial movement or a rotating or a combining rotating and axial movement.

The invention makes it possible for the hitherto necessary intermediate elements, such as sliding blocks and supporting of the connecting-rods in the sliding block, to be eliminated. This gives the advantage that there are fewer sources of defects and a considerably greater accuracy of working is obtained, which makes it possible to

maintain close tolerances in the workpieces. Further, by the arrangement of the individual connecting-rods in the guiding of the swinging disk, the swinging movement of the former with respect to the workpiece is removed. In this way, an exact shaping of the workpiece in accordance with the shape of the tool is obtained.

The accompanying drawing shows by way of example one form of execution of the object of the invention diagrammatically, Fig. 1 being a section of the arrangement along the line I—I in Fig. 2 and Fig. 2 a section along the line II—II in Fig. 1.

As can be seen from the drawing, the numeral 1 designates the eccentric of one of the connecting-rods 2, of which several, for instance four can be provided arranged round the hole 3 receiving the workpiece 4. The eccentric 1 has two pins 5 which rotate in bearings 6 and drive the eccentric 1. Each eccentric is fitted in an eccentric strap 7 which is firmly connected to the connecting-rod 2 by a screw-cap 8. The connecting-rod head 9 is, for instance, suitably shaped with four sides and slides as a holder of the tool 10 in a corresponding opening 11 in a carrier 12, which is here shown as a disk and is rotatably supported at 14 round the holes 3 for receiving the workpiece 4. As can be seen from Fig. 2, the carrier 12 has for instance four such openings 11, each of which serves as a guideway for a hammer tool carrier 10 fitting exactly said opening 11. The work-piece is held by a work holder 15 which is designed in such a way that the workpiece, exactly like the carrier disk 12, partakes in the oscillatory movements within the limits of an angle which comprises only a few degrees. This angle corresponds to eccentricity of the eccentric 1. In addition to the oscillatory movement, the work holder 15 is movable axially and rotationally. Without departing from the scope of the invention, the technical details as given in the specification and drawing may be replaced by their technical equivalents.

What I claim is:

1. In apparatus for the rapid forging of work-pieces of symmetrical cross-section, the combination of a base, a guide member rotatably mounted on the base and having a central hole to receive the work, a plurality of rotatable shafts disposed equidistant around said guide member with their axes parallel to one another and to the axis of said hole, an eccentric on each of said shafts and an equal number of hammer tool carriers slidably mounted on said guide member in angularly spaced relation around said holes, each of said tool carriers being slidable radially of the guide member and having at its inner end a work-engaging tool and at its outer end a sleeve rotatably engaging one of said eccentrics, whereby simultaneous rotation of said shafts produces reciprocation of the tool carriers and tools and oscillation of the guide member.
2. In apparatus for the rapid forging of work-pieces, the combination of a base, a support for a work-piece, a guide member rotatably mounted on the base for rotation about the longitudinal axis of the work-piece, a tool carrier slidably mounted on the guide member for reciprocatory movement in a radial direction toward and away from the work-piece, a forging tool fixedly carried on the inner end of said carrier, a sleeve carried on the outer end of said carrier, an eccentric carried on a shaft and rotatable in said sleeve, and bearing means for rotatably supporting said shaft, whereby rotation of the shaft and eccentric produces reciprocation of the tool carrier and tool and oscillation of the guide member about its axis of rotation.

AUGUST SAXER.
